UNITED STATES PATENT OFFICE.

SIDNEY W. FARNSWORTH, OF CHICAGO, ILLINOIS, ASSIGNOR TO WESTINGHOUSE ELECTRIC & MANUFACTURING COMPANY, A CORPORATION OF PENNSYLVANIA.

REFILLABLE FUSE.

Application filed June 21, 1918. Serial No. 241,258.

To all whom it may concern:

Be it known that I, SIDNEY W. FARNSWORTH, a citizen of the United States, and a resident of Chicago, in the county of Cook and State of Illinois, have invented a new and useful Improvement in Refillable Fuses, of which the following is a specification.

My invention relates to fuses and particularly to fuses of the refillable type.

10 One object of my invention is to provide a refillable fuse in which the permanent conducting parts shall be prevented from becoming coated with oxides resulting from repeated operation of the fusible elements 15 of the same.

Another object of my invention is to provide a fuse that shall comprise permanent members and a plurality of fusible elements severally disposed in renewable auxiliary 20 receptacles.

A further object of my invention is to provide a fuse that shall be ruptured at a plurality of points to reduce the violence of the attendant explosion.

25 A still further object of my invention is to prevent burning of the insulation of refillable fuses in which repeated operation is likely to result in the formation of relatively free paths between the arc flame and 30 surrounding bodies.

Heretofore, refillable fuses have usually been constructed of insulating tubing, to the ends of which terminal members have been screw-threaded or otherwise attached 35 and in which there has been free communication between the fusible elements and the terminal members or other conducting parts. This construction permitted the accumulation of oxides upon the permanent conducting 40 members to which the fusible elements were attached, with the result that, after a relatively few operations, the added resistance of the circuit was of such value as to abnormally heat the elements and thereby 45 cause them to be ruptured at current values much below that at which they were designed to operate. Further, the repeated passage of flame between the terminal cap threads or other spaces between the caps 50 and the insulating receptacles very often burned away a sufficient quantity of the insulating material to establish dangerous fire paths to surrounding bodies.

In practicing my invention, I so segregate

a plurality of renewable fusible elements 55 from the permanent parts of a fuse device, by enclosing the same in auxiliary renewable receptacles, as to prevent the accumulation of oxides upon the conducting parts and the burning of the insulating material 60 thereof.

The single figure is a view, partially in elevation and partially in section, of a fuse device embodying my invention.

A hollow cylindrical receptacle 1 of insulating material, such as fiber or other suitable substance, is exteriorly screw-threaded at its ends to receive cooperating cap members 2 having end recesses 3, through which terminal members 4 extend, and inwardly 70 projecting flanges 5 which have overlapping engagement with outwardly projecting flanges 6 upon the members 4 to hold the latter in position.

A cylindrical conducting member 7, preferably of copper, but which may be of any other suitable material, is concentrically disposed within the member 1 and extends substantially equal distances longitudinally from the center of the member 1. Auxiliary 80 receptacles 8 comprising discoidal end plates 9, of copper or other suitable material, and hollow cylindrical side walls 10, of fiber or other suitable insulating substance, are disposed between the ends of the member 7 and 85 the inner ends of the members 4. The terminal members 4, receptacles 8 and the member 7 are placed in rigid co-axial relation in the receptacle 1 by properly screwing the cap members 2 thereon. Fusible elements 11 are disposed within the auxiliary receptacles 8 and extend between the plates 9 to which they may be secured in any suitable manner. A conducting path through the device is provided from the terminal 95 members 4 through the plates 9, elements 11 and the member 7. Holes 12 and 13 may be provided in the plates 9 and in the parts 1 and 7, respectively, to permit the escape of arc gases.

When a short circuit occurs, the elements 11, being in series relation and of the same cross-sectional area, are ruptured simultaneously, thereby doubling the counter-electromotive force in the circuit and reducing the explosive force caused by the arc. A small or gradually increasing overload 105 may cause but one of the elements 11 to be

ruptured, thus necessitating the renewal of but one of the same. Inasmuch as the fusible elements are enclosed in auxiliary receptacles, that are replaced by new ones after each operation, accumulation of oxides on the permanent conducting parts of the device and the burning of the permanent insulating parts are avoided. In this manner, the efficiency of the device is maintained by reason of the fact that the fusible elements are ruptured at the current value for which they are designed, and the danger from fire to surrounding bodies is eliminated.

15 While I have shown and described a particular form of my invention, many changes may be made therein without departing from the spirit and scope thereof, as set forth in the appended claims.

20 I claim as my invention:

1. The combination with a unitary fuse structure comprising a receptacle and terminal members closing the ends thereof, of a fuse element comprising a plurality of alternately disposed unattached series-related fusible and normally non-fusible members extending between said terminal members in said receptacle, said element being rupturable at a plurality of places simultaneously.
- 25 2. The combination with a unitary fuse structure comprising a main receptacle and terminal members closing the ends thereof, of a plurality of enclosed auxiliary cartridge fuse receptacles disposed in said main receptacle and connected in circuit relation to said terminal members.
- 30 3. The combination with an enclosed fuse structure comprising an insulating receptacle and terminal members substantially closing the ends thereof, of a conducting member disposed at an intermediate position in said receptacle, and a removable unattached fuse element disposed between each of said terminal members and said conducting member.
- 35 4. The combination with an enclosed fuse structure comprising a hollow cylindrical insulating receptacle and main terminal members disposed at the ends thereof, of a hollow cylindrical conducting member centrally disposed in said receptacle and two renewable fuse elements each disposed between, and engaging, one end of said conducting member and one of said terminal members, each of said renewable fuse elements comprising an insulating receptacle, auxiliary terminal members closing the ends thereof and a fusible member disposed there-

in and engaging said auxiliary terminal members.

5. In a fuse device, the combination with a plurality of independent cartridge fuse structures each comprising a tubular receptacle and terminal members closing the ends thereof, of means for supporting said structures in end-to-end relation to constitute a single fuse device having a plurality of fusing points.

6. In a cartridge fuse device, the combination with a main receptacle and terminal members closing the ends thereof, of a plurality of auxiliary cartridge fuse devices, each comprising a receptacle and terminal members closing the ends thereof, disposed in end-to-end relation between the terminal members of said main receptacle.

7. In a cartridge fuse device, the combination with a main receptacle and terminal members closing the ends thereof, of a plurality of auxiliary cartridge fuse devices, each comprising a receptacle and terminal members, disposed in spaced series relation between the terminal members of said main receptacle, and means for operatively connecting said auxiliary devices.

8. The combination with a unitary fuse structure comprising a tubular receptacle and terminal members closing the ends, of a plurality of unattached fuse elements disposed within the receptacle and held in conductive relation between the terminal members.

9. The combination with a unitary fuse structure comprising a receptacle and terminal members associated therewith, of a plurality of unattached fuse elements disposed within the receptacle and held in conductive relation by the terminal members.

10. The combination with a unitary fuse structure comprising a receptacle and terminal members associated therewith at least one of which is adjustable, of a plurality of unattached fuse elements disposed within the receptacle and adapted to be clamped in conductive relation by the terminal members.

11. The combination with a unitary fuse structure comprising a receptacle and terminal members associated therewith, of a fuse element comprising a plurality of unattached fusible and normally non-fusible members disposed between the said terminals and thereby held in conductive relation.

In testimony whereof, I have hereunto subscribed my name this 7 day of Jan. 1920.

SIDNEY W. FARNSWORTH.
